WOODBORING TOOL

William McMahon, Lidcombe, near Sydney, New South Wales, Australia

Application May 24, 1934, Serial No. 727,344
In Australia February 19, 1934

3 Claims. (Cl. 145—122)

This invention relates to tools for woodworking, and the object thereof is to provide a tool for the formation of square or other "cornered" recesses or apertures in wood, or for the formation of squared ends to elongated recesses or apertures as in mortise work.

In order to fully describe the invention reference is made to the accompanying drawing which depicts an embodiment suitable for forming square holes, and in which

Figure 1 is a perspective view of the tool,

Figure 2 a longitudinal cross-sectional elevation thereof on plane 2—2 of Figure 1,

Figure 3 a longitudinal fragmentary cross-sectional elevation of the tool, during operation, taken on the plane 3—3 of Figure 1, at right angles to the section of Figure 2,

Figure 4 a cross-sectional view taken on line 4—4 of Figure 3, shewing a detail,

Figure 5 a fragmentary perspective view shewing a modification, and

Figure 6 a longitudinal cross-sectional elevation taken on plane 6—6 of Figure 5.

The tool illustrated in Figures 1, 2, 3, and 4 includes an elongated punch 1 of square external section and with a cylindrical bore 2 formed therethrough. The lower end of punch 1 is formed with cutting edges 3 to punch a square aperture through the woodwork. Chip escape apertures 4, 4 are formed through opposite sides of the punch, and at the upper end a collar 5 is threaded thereon.

A woodboring twist-bit 6 is neatly mounted for rotation in the internal bore 2 of the punch, the lower end 7 of the bit projecting slightly past the cutting edges 3 of the punch. A collar 6¹ is formed on the bit just above chip apertures 4, to force the chips through said apertures.

The upper end 8 of the bit 6 projects through the upper end of the punch 1 and collar 5, where the cylindrical lower end 9¹ of a bit-head 9 is threaded thereon. The diameter of the cylindrical bit-head 9 is increased at its upper end 10 with the formation of a shoulder 11, and a tapered chuck engaging shank head 12 is formed on the extreme upper end thereof.

A hollow cylindrical hammer 13 is mounted about the bit-head 9 for longitudinal and rotational oscillation thereon, the internal bore of the hammer being a neat sliding fit on the larger diameter 10 of the bit-head, and an internal flange 14 at the lower end of the hammer being a sliding fit on the smaller section 9¹ of the bit-head.

55 A compression coil spring 15 is located between

the smaller section 9¹ of the bit-head and the surrounding hammer 13, the spring bearing at its ends respectively upon the shoulder 11 of the bit-head and the flange 14 of the hammer, and thus operating to force the lower end of the hammer against the shoulder 5 on the punch 1. A guide pin 16 threaded into the lower end of hammer 13, and passing through an aperture 17 in flange 5 of the punch 1 prevents rotation of the hammer in relation to the punch, but does not impede longitudinal oscillation in relation to the same.

A cam track is formed in the larger section 10 of the bit-head 9, the track consisting a gradually rising portion 18 which terminates in a vertical drop section 19. This cam track is duplicated, diametrically opposite on section 10, by rising portion 18¹ and vertical drop section 19¹. A set screw 20 is threaded through the wall of hammer 13 and the nose 21 of this set screw engages in the cam track. The set screw is duplicated at 20¹, diametrically opposite in the hammer 13.

In order to permit reverse rotation of bit 6 independently of the punch 1 to facilitate disengagement from the wood after boring has terminated, a clear annular recess 10¹ is formed in portion 10 immediately above the apexes of the cam tracks 18 and 18¹. To effect such reversal, hammer 13 is retracted to the position shewn in Figure 3, when the set screws 20 and 20¹ register with the annular recess 10¹, and the bit-head 9 with its cam tracks may be reversed without interference from the set screws.

In order to provide means to readily maintain the hammer 9 in this retracted position during reversal of the bit, a shallow arcuate recess 21 is formed in the upper face of shoulder 5, and in communication with aperture 17 (Figure 4). When it is desired to retain the hammer 13 in retracted position it is simply rotated slightly from this position to bring the nose of pin 16 in recess 21, where it remains during reversal of the bit, and whence it is released by a partial turn of the hammer to once more align pin 16 with its slot 17.

The operation of the tool is as follows:

The shank head 12 of the bit-head is introduced into a drill (or brace) and the nose of the tool is applied to the woodwork. The punch 1 is manually held against rotation and the drill is rotated, causing the bit head 9 and the bit 6 to similarly rotate and the latter to bore into the woodwork. As the bit-head revolves, the engagement of the noses of set screws 20 and 20¹ in the cam tracks 18 and 18¹ holds the hammer 13 in its retracted position.

and 18¹ causes the hammer 13 to slide longitudinally on the bit-head 9 and to be retracted from the collar 5 (as shewn in Figure 3) compressing spring 15: in this figure the set screw 20¹ is shewn 5 to have just risen to the apex of cam track 18¹ and to be about to drop down vertical section 19¹. When the vertical drop sections 19 and 19¹ of the cam track reach the set screws, the spring 15 snaps 10 the hammer 13 down on the collar 5, delivering a heavy impact blow to the punch 1 and causing the sharpened edges 3 of the same to bite into the woodwork and shape the round hole drilled by the bit 6 into a neat square hole. The chips from the bit 6 and punch 1 are discharged through the 15 apertures 4, 4 in the punch.

During each revolution of the bit 6 the hammer 13 will rise and fall twice, the number of vertical drop sections of the cam track (such as 19 and 19¹) 20 obviously determining the number of blows imparted by the hammer 13 to the punch 1 during each such revolution.

In certain cases, such as when the tool is being constantly used on hardwood, it may be necessary to renew the punch 1. To facilitate and 25 cheapen such renewal, the nose of the punch may be detachable, as shewn in Figures 5 and 6. The nose 24 of the punch is square, as heretofore, and at its upper end 25 is internally threaded and screws on to an external thread on the lower end 30. 25 of a hollow cylindrical punch tube 27 and abuts against a collar 28 on said tube.

The bit 6 is normal at its lower end, but is reduced in diameter at 29 where it lies within the smaller internal diameter of the punch tube 27. 35 By means of this construction the nose 24 is detachable and consequently renewable at lower cost than would be the whole punch 1 of the construction shewn in Figures 1, 2, and 3.

I claim:

40 1. A woodboring tool comprising a hollow punch with a sharpened extremity, a woodboring bit rotatably mounted within said punch, a hammer slidably mounted in relation to said punch, cam

means actuated by rotation of the bit for retracting said hammer in relation to said punch, and a spring adapted to move said hammer from such retracted position to impart a blow to said punch during said rotation of the bit.

2. A woodboring tool comprising a hollow punch of rectangular external section and with a cylindrical bore therethrough, a shoulder on said punch remote from the operative end thereof, a woodboring bit rotatably mounted in said bore and 10 passing through said shoulder, a bit-head secured on said bit, a cylindrical hammer axially reciprocable in relation to said punch and having rotational and reciprocable bearing on the bit-head, a spring urging said hammer into contact with 15 said shoulder, and means including a cam track actuated by rotation of the bit-head in relation to the punch to retract said hammer from said shoulder and to permit the spring to return the hammer against said shoulder to impart a blow 20 to the punch during the said rotation of the bit.

3. A woodboring tool comprising an elongated punch of square external section formed with a cylindrical bore therethrough, a cutting edge on one end of said punch and a shoulder on the other 25 end, a woodboring bit rotatably mounted within said bore and protruding through said shoulder, a bit-head secured on the bit outside said shoulder, a cylindrical hammer slidably and rotatably mounted on said bit-head and adapted to contact with said shoulder, means for restraining rotation of said hammer in relation to said punch, a spring urging said hammer into contact with said shoulder, and a cam track formed in said bit-head and engaged by an element in said hammer 35 for the purpose of retracting said hammer from said shoulder during rotation of the bit in relation to the punch, characterized in that a portion of said cam track is formed to permit the spring to return the hammer to the shoulder from the 40 retracted position.

WILLIAM McMAHON.
